United States Patent Office

Des. 194,071
Patented Nov. 13, 1962

194,071

BOTTLE

Douglas W. Anderson, Palatine, and William M. Goldsmith, Highland Park, Ill., Hal L. Hester, Munster, Ind., and Joseph J. Ortega, Chicago, Ill., assignors to Simoniz Company, Chicago, Ill., a corporation of Delaware

Filed Feb. 23, 1962, Ser. No. 68,923

Term of patent 14 years

(Cl. D58—6)

The dominant features of our design reside in the portions shown in full lines.

We claim:

The ornamental design for a bottle, as shown and described.
